UNITED STATES PATENT OFFICE

158,242

SMOKING STAND TRAY UNIT

Gustaf E. Andre, Chicago, Ill.

Application July 1, 1949, Serial No. 3,656

Term of patent 14 years

(Cl. D85—2)

To all whom it may concern:

Be it known that I, Gustaf E. Andre, a citizen of the United States, residing in Chicago, in the county of Cook and State of Illinois, have invented a new, original, and ornamental Design for a Smoking Stand Tray unit, of which the following is a specification, reference being had to the accompanying drawings, forming part thereof.

Fig. 1 is a perspective view thereof; and

Fig. 2 is a top plan view of a smoking stand tray unit showing my new design.

I claim:

The ornamental design for a smoking stand tray unit, as shown.

GUSTAF E. ANDRE.
